UNITED STATES PATENT OFFICE.

HERBERT H. DREW, OF WATERLOO, WISCONSIN.

COUPLING.

1,380,468.

Specification of Letters Patent. Patented June 7, 1921.

Application filed November 29, 1918. Serial No. 264,558.

To all whom it may concern:

Be it known that I, HERBERT H. DREW, a citizen of the United States, and resident of Waterloo, in the county of Jefferson and State of Wisconsin, have invented certain new and useful Improvements in Couplings; and I do hereby declare that the following is a full, clear, and exact description thereof.

My invention relates to new and useful improvements in coupling devices, particularly those forms which are for uniting the sections of piping or cylindrical bars and the like.

In the construction of sanitary cow stalls and similar constructions and in the formation of knock down pens of various kinds, it has usually been necessary to employ couplings cast from malleable iron or steel. Such couplings are usually internally screw threaded to receive the threaded ends of the pipe sections and are therefore not adjustable to any great degree. They are also prone to crack when any considerable amount of strain is placed on the same. A further objection to their use is their expensiveness.

The idea of the present invention is to overcome these disadvantages by providing a simply constructed, yet very strong coupling made from a single piece of sheet metal. In carrying out the invention a metal blank is stamped into shape by suitable machinery, and after this formation the bars or piping which is to be connected thereby is adjustably secured in place by suitable fastening elements.

With these general objects in view the invention resides in the novel formation and arrangement of parts shown in the accompanying drawing and hereinafter more particularly described and claimed.

In the drawing:

Figure 1 represents a side elevational view of a T coupling constructed in accordance with my invention and having a pair of pipe sections secured together thereby.

Fig. 2 is an edge view of the parts shown in Fig. 1, one of said pipe sections being in cross section.

Fig. 3 is a cross sectional view on the line 3-3 of Fig. 1, and

Fig. 4 is a detail plan view of the sheet metal blank from which the coupling is formed.

Referring more particularly to the draw-

ing wherein similar reference characters indicate like parts throughout the several views, the numerals 1 and 2 designate respectively a pair of pipe sections which are to be held by a coupling formed from the blank 3 shown in Fig. 4. It will be noted that this blank is substantially rectangular in plan view, although if desired, its opposite corners may be cut away as shown at 4 in Figs. 2 and 4.

To form the coupling the blank 3 is first bent upon itself midway its ends, as shown at 5, and the consequent arms 6 thus procured are bent longitudinally into substantially semi-cylindrical shape with the concave sides toward each other. This curvature of the arms 6 is continued from their free ends to points spaced from the bend 5 as at 7.

The portions of the blank adjacent the bend 5 and between said bend and the points 7 are bent into substantially transversely cylindrical shape to thereby form a sleeve 8. This sleeve is adapted to slidably receive the section of piping 2, whereas the socket 9, formed by the curved arms 6, receives the section of piping 1. The section 1 is adapted to be rigidly secured in the socket 9, while the other section is permitted sliding movement in the sleeve, or the sleeve is allowed to slide on the same, depending upon whether the section 2 is stationary or movable, to permit adjustment of one or the other.

The means for holding the sleeve 8 and the section 2 in adjustable positions relative to each other is procured by a set bolt 10, the shank of which is screw threaded to engage similar threads in a bushing 11 which is disposed in a circular opening 12 in the sleeve 8. This bushing is held against rotation by an annular flange 13 that extends from one end and is curved to conform to the curvature of the bend 5, as most clearly shown in Fig. 3. Thus upon inner movement of the set bolt 10 its inward end is brought into engagement with the section 2 and bites into the same to hold the members against relative movement.

The section 1 is held in the socket 9 and the arms 6 which comprise the socket are secured against spreading apart by a bolt 14 which extends transversely therethrough and is provided with a nut 15. When this bolt is once in position the section 1 and

coupling are held against movement relative to each other inasmuch as it is not necessary to frequently adjust these two parts.

From the foregoing description it is obvious that a very simply constructed T coupling has been produced from a single rectangular piece of sheet metal which will have a great many advantages over the ordinary cast coupling of similar shape. Although the coupling shown in the drawing has the axis of the socket 9 disposed at right angles to that of the sleeve 8, it is obvious that these two parts may be disposed at other angles without departing from the objects of the present invention as defined in the appended claim.

I claim:

A coupling of the class described formed from a single piece of sheet metal bent upon itself, the portion of the piece adjacent the bend being transversely substantially cylindrical to receive a section of cylindrical piping, the free end portions of the piece being

longitudinally substantially semi-cylindrical with their concave sides toward each other to provide a socket for the reception of the end of a second section of cylindrical piping, said cylindrical portion of the piece having an aperture, a bushing extending through said aperture and loosely mounted therein, a flange on the inner end of said bushing between the cylindrical portion and said section of cylindrical piping, said flange being curved to conform to the curvature of the latter to prevent rotation of the same, a set bolt adjustable in said bushing and movable toward and into engagement with the first mentioned section of cylindrical piping, and means for holding the free end portions of the piece against spreading apart.

In testimony that I claim the foregoing I have hereunto set my hand at Milwaukee, in the county of Milwaukee and State of Wisconsin.

HERBERT H. DREW.
